CLAIM

The ornamental design of powered external vacuum appliance for the treatment of impotence, as shown and described.

DESCRIPTION

FIG. 1 is a back end elevational view of the vacuum cylinder component of a powered external vacuum appliance for the treatment of impotence, embodying our new design; FIG. 2 is a top plan view thereof, the bottom plan view being identical thereto; FIG. 3 is a right side elevational view thereof, the left side elevational view being identical thereto; FIG. 4 is a front end elevational view thereof; FIG. 5 is a back end elevational view of the cylinder mount and pump housing component of the powered external vacuum appliance for the treatment of impotence; FIG. 6 is a right side elevational view thereof, the left side elevational view being identical thereto; FIG. 7 is a top plan view thereof; FIG. 8 is a bottom plan view thereof; FIG. 9 is a front end elevational view thereof; and, FIG. 10 is a right side elevational view of the vacuum cylinder component and the cylinder mount and pump housing component in combined condition.
